J. M. SEARLE.

EXHAUST CONDENSER FOR STEAM EXHAUST PIPES.

APPLICATION FILED MAR. 31, 1908.

Patented Sept. 15, 1914.

1,110,461.

UNITED STATES PATENT OFFICE.

JOSEPH M. SEARLE, OF PITTSBURGH, PENNSYLVANIA.

EXHAUST-CONDENSER FOR STEAM-EXHAUST PIPES.

1,110,461.

Specification of Letters Patent. Patented Sept. 15, 1914.

Application filed March 31, 1908. Serial No. 424,319.

To all whom it may concern:

Be it known that I, JOSEPH M. SEARLE, of Pittsburgh, Allegheny county, Pennsylvania, have invented a new and useful Exhaust-Condenser for Steam-Exhaust Pipes, of which the following is a full, clear, and exact description, reference being had to the accompanying drawings, forming part of this specification, in which—

10 Figure 1 is a section of my condenser; Fig. 2 is a horizontal section on lines II—II of Fig. 1; Fig. 3 is a vertical section on the line III—III of Fig. 1 with the interior member omitted; and Fig. 4 is a horizontal 15 section of a modification of my invention.

My invention relates to exhaust condensers and has for its object to provide a condenser of efficient, simple and cheap construction, which may be used at or near the 20 foot of the exhaust pipe instead of at the top, as is the common practice, and is adapted to return the water precipitated by the condensation of the steam with substantially no loss to the boiler.

25 A further object attained is the prevention of the escape of the steam from the head of the exhaust pipe and of the consequent uncontrolled precipitation of the moisture present in the steam, which often results in 30 damage to adjacent properties.

Referring to the drawings, the steam intake pipe 2 leading from the engine or heater (not shown), has a flaring mouth 3 secured by bolts 4 to the condenser 5, which 35 is positioned at the foot of the exhaust pipe 7 and fastened thereto by bolts 8. The walls of the condenser 5 are formed by a metal U-shaped shell 9 which is positioned on the supporting member 10, located in the drip 40 pan 11. In the opening 12 of the condenser 5 over which the flaring mouth 3 is bolted is a plate or diaphragm 13, having two series of oblique parallel ribs 14 the two series meeting at the center from which they 45 are inclined in opposite directions with corresponding grooves 15 between them. The diaphragm 13 is secured at its top and bottom to the shell 9 and leaves the opening 12 unobstructed at the sides 16 and 17 thereof.

50 Located centrally in said condenser and below the exhaust pipe 7; and leading thereto is a cylindrical member 18, positioned upon the supporting member 10, and with the opening therein corresponding to the 55 opening 19 of the member 10. Said cylindrical member 18 has a plurality of series

of vertically inclined apertures 20, with the apertures of one series staggered or otherwise with relation to the apertures of each adjacent series. 60

In operation, the steam from the intake pipe 2 impinges directly against the diaphragm 13, changing the course of the steam and separating the oil and water therefrom before it strikes the cylindrical member 18. 65

The oil and water being precipitated, pass into the shell of the condenser through the opening 21, while the steam passes into the condenser 5 through openings 16 and 17 at the sides of the diaphragm 13 where a partial condensation of the steam takes place 70

by contact with the cylindrical member 18. The steam from this chamber passes through the openings 20 into the cylindrical member 18 and passes upwardly into the exhaust 75

pipe 7. The water and oil from this chamber will pass to the drip pan 11 through openings 22 and 19. The upward movement of the steam within the cylindrical member will cause a suction at the bottom thereof 80

and air will be drawn into said member through the opening 19. This action of the steam is similar to the well-known vacuum producing action of a steam jet. This constant inrush of relatively cold air into the 85

member 17 not only cools the walls of said member and increases its condensing action, but this air is directly commingled with the steam entering said member. In this manner there is an efficient condensing action 90

both exteriorly and interiorly of the said member. The condensation within the member 18 tending to produce a vacuum also increases the flow of both air and steam therein. The water of condensation in the pipe 7 95

and cylindrical member 18 will also flow into the drip pan 11, from which it can be drawn through the pipe 23 connected to the lower end thereof and can be returned to the boiler after the oil has been separated therefrom. 100

In Fig. 4 I show a modification in which I use a condenser without the diaphragm 13, and in which I have shown a cylindrical shell or condenser 5 which is concentric with the cylindrical member 18. 105

Many changes may be made in the apparatus which I have described and shown, without departing from my invention, since

What I claim is—

110 1. A vertically disposed steam exhaust pipe having a condenser at its lower end,

said pipe extending a suitable distance above the condenser and communicating with said condenser at its lower end for admitting steam from the condenser to the pipe, said condenser having an inlet opening for the steam, the condenser also having an opening to the atmosphere at its lower end for admitting air at atmospheric temperature to the condenser and pipe to reduce the temperature of the steam and cause condensation of the steam before it reaches the top of the pipe; substantially as described.

2. A vertically disposed steam exhaust pipe having a discharge to the atmosphere at its upper end, a condenser connected to said pipe at its lower end, said condenser having inner and outer chambers, there being an inlet to the condenser for the steam, the pipe extending a suitable distance above the condenser, the condenser also having an opening to the atmosphere at its lower end for the admission of air at atmospheric temperature, there being a plurality of upwardly extending openings in the inner wall of the condenser to permit the steam to pass from the outer chamber to the inner chamber, which openings act as injectors for drawing the air through the bottom of the condenser into contact with the steam for condensing the same; substantially as described.

3. A vertically disposed steam exhaust pipe having a condenser connected to its lower end, said condenser consisting of a chamber connected with the exhaust intake pipe, a cylindrical member in said chamber opening into the exhaust pipe and having a plurality of upwardly extending openings for admitting steam from the chamber to the cylindrical member, said cylindrical member being open to the atmosphere at its lower end to admit air at atmospheric temperature thereto by the injector action of the upwardly extending openings, the commingling of the air with the steam within the cylindrical member and exhaust pipe causing the same to condense before it reaches the top of the pipe, and a receptacle

at the lower end of said cylindrical member for the water of condensation from the condenser, substantially as described.

4. A vertically disposed steam exhaust pipe having a condenser connected to its lower end, said condenser consisting of a chamber connected with the exhaust intake pipe, a cylindrical member in said chamber opening into the exhaust pipe and having a plurality of upwardly extending openings for admitting steam from the chamber to the cylindrical member, said cylindrical member being open to the atmosphere at its lower end to admit air at atmospheric temperature thereto by the injector action of the upwardly extending openings, the commingling of the air with the steam within the cylindrical member and exhaust pipe causing the same to condense before it reaches the top of the pipe, a separating diaphragm within said chamber, and a receptacle at the lower end of said cylindrical member for the water of condensation from the condenser; substantially as described.

5. The combination with a vertically disposed steam exhaust pipe of a condenser connected to the lower end of said exhaust pipe, said condenser having a chamber provided with an inlet connection for exhaust steam, a cylindrical member or tube extending vertically through the chamber and communicating with the exhaust pipe at its upper end and open to the atmosphere at its lower end, there being a plurality of rows of upwardly extending openings through said cylindrical member for admitting steam from the chamber to the cylindrical member, and a drip pan at the lower end of said cylindrical member for receiving the water of condensation from the condenser and exhaust pipe; substantially as described.

In testimony whereof, I have hereunto set my hand.

J. M. SEARLE.
